UNITED STATES PATENT OFFICE

MITCHELL B. WALKER, OF GREENSBORO, NORTH CAROLINA

LUBRICATING MECHANISM

Application filed March 26, 1929. Serial No. 350,033.

The present invention appertains to a new and useful improvement in lubrication, and more particularly to improved means for force feeding lubricant to remotely located 5 bearings.

This invention is especially adapted for use on automobiles, where a centralized feeding mechanism would be far more convenient and practical than the necessary lubricating of each individual bearing by hand.

An important object of the invention is to provide a lubricating mechanism which will be substantially automatic in operation.

Another important object of the invention 15 is to provide a lubricating mechanism which will be of low cost, to manufacture due to its extremely brief construction.

These and other objects of the invention will become more apparent to the reader 20 after considering the invention as described and claimed hereinafter.

In the drawings:

Figure 1 represents a rear side elevation of the usual cowl wall of an automobile body 25 with the improved mechanism mounted thereon.

Fig. 2 represents a partial side elevation and sectional view of the improved mechanism.

Fig. 3 is a top plan view of the lubricating mechanism.

Fig. 4 is a horizontal sectional view thru the lower portion of the mechanism.

Fig. 5 is a fragmentary vertical sectional 35 view of the lower portion of the mechanism.

Fig. 6 is a fragmentary vertical sectional view through one of the pump devices of the mechanism.

Fig. 7 is a horizontal sectional view, taken 40 substantially on the line 7-7 of Fig. 6.

Fig. 8 is a perspective view of the plunger employed in the pump devices.

Referring to the drawings wherein like numerals designate like parts, the present invention includes a gear chamber 3 provided 45 at its inner side and adjacent its open top with a shoulder 4.

Extending into the gear chamber 3 and for rest upon the shoulder 4 is a lubricant 50 container 5. The container is provided with

the bottom wall 6 and the top wall 7 and has a plurality of cylinders 8 extending vertically through these walls and depending for a substantial distance into the gear chamber 3, substantially as shown in Fig. 2.

These cylinders are arranged in the annular formation shown in Fig. 3, and each is provided with a shoulder 9 for engagement against the bottom side of the wall 6, while its upper end is threaded to receive the nut 10 which is adapted to be urged against the top surface of the wall 7 to firmly maintain the cylinder in position.

Adjacent the bottom wall 6, the cylinder 8 is provided with a lubricant inlet opening 11 while situated immediately above the inlet opening 11 and within the cylinder 8 is a valve seat structure 12 against which the ball 13 is normally seated and tensionally thus maintained by the coiled spring 14. The coiled spring 14 impinges at its upper end against the plug 15 threadedly engaged within the upper end of the cylinder 8 for connecting the discharge tube 16 to the cylinder.

A plunger 17 is slidably engaged within the portion of the cylinder depending within the gear chamber 3 and is provided with a convex-shaped head 18 at its lower end. A coiled compressible spring 19 is interposed between the head 18 and the shoulder 9 on the cylinder 8. The spring is adapted to normally maintain the plunger 17 in a position so as to establish communication between the interior of the cylinder 8 and the interior of 75 the lubricant chamber 5 through the opening 11.

A barrel 20 depends from the bottom of the gear chamber 3, and contains a rotatably mounted body 21 of suitable di-electric material. The lower end portion of the body 21 carries a plurality of circumferentially spaced contact plates 22, preferably equal in number to the number of pump devices. The lower end portion of the body 21 carries an insulating ring of fibre with one ground contact, which is to show a telltale light when the device has made one complete revolution, which, of course, means that the lubricant has been forced to all points. A binding post 23 90

has its post portion 24 disposed through the wall of the barrel 20 and is adapted for wiping engagement with the plate 22. The plate 22 and the binding post 23 are in a suitable tell-tale light or alarm circuit, (not shown in the drawings).

Mounted within the lower portion of the gear chamber 3 is a grooved gear 25 mounted upon the ball bearing structure 26. A cam structure 27 of arcuate disposition is located upon the gear 25 in the manner clearly shown in Fig. 4. The radius of the curved cam is substantially the same as the circle described by the annular arrangement of pump devices 15 and is substantially concentric therewith. The gear turn chamber 3 has an offset 28 in its lower portion to accommodate a worm 29 for meshing with the gear 25.

As is shown in Fig. 1, a suitable bracket 30 secured to the bottom of the gear chamber 3, extends laterally with respect thereto and has an upstanding post 31 thereon for supporting an electric motor 32. The armature shaft 33 of the motor extends through the side wall of the gear chamber 3 and the offset portion 28 thereof and has the worm 29 keyed thereto.

It will thus be seen that when the motor 32 is energized, the rotation of the shaft 33 and gear 29 will revolve the gear carried cam 27. The cam as it rides against the heads 18 of the plungers 17 will cause the plungers on the pump devices to move upwardly in their respective cylinders to force the lubricant 35 contained therein past the aforementioned check valve and out through the discharge tube 16 to the corresponding parts of the vehicle to be lubricated.

In Fig. 2 it will be seen that the gear chamber 3 is provided with upstanding threaded members 34 for disposition through apertured ears 35 on the lubricant container 5. Nuts 36 are engageable on the threaded members 34 and may be removed to permit the dis- 45 assembly of the mechanism.

Obviously the present invention involves numerous novel features and advantages over the art, and it is to be understood that various changes in the specific, shape, and size, and 50 materials, may be resorted to without departing from the spirit and scope of the invention as claimed hereinafter.

Having thus described my invention, what I claim as new is:—

55 In a lubricator, a reservoir adapted for the reception of a lubricant and being provided with a plurality of pumping units having longitudinally movable plungers extending out through the lower end of the reservoir, a casing 60 suspended from the reservoir, means detachably connecting the casing to the lower portion of the reservoir, a rotatable element mounted within the lower portion of the casing and being carried thereby and having an arcuate cam for successive engagement with

said plungers, a driving mechanism carried by said casing and having operative connection with said rotatable elements, said rotatable elements and said driving mechanism being removable with said casing.

In testimony whereof I affix my signature.

Mitchell B. Walker.
